EXPANSIBLE LINK CHAIN FOR A BRACELET
OR THE LIKE

Max Jacoby, Lawrence, N. Y., assignor to Jacoby-Bender, Inc., New York, N. Y., a corporation of New York

Application June 1, 1949, Serial No. 2,986

Term of patent 7 years

(Cl. D45—4)

To all whom it may concern:

Be it known that I, Max Jacoby, a citizen of the United States and a resident of Lawrence, Long Island, county of Nassau and State of New York, have invented a new, original, and ornamental Design for an Expansible Link Chain for a Bracelet or the like, of which the following is a specification, reference being had to the accompanying drawing, forming a part thereof, in which:

Fig. 1 is a top view of the expansible link chain, in contracted condition, showing my new design;

Fig. 2 is a top view thereof in partially expanded condition, portions of the conventional bottom links being visible between the top links;

Fig. 3 is a side elevational view, on an enlarged scale, of one of the individual top links of the chain taken from the left hand side of Fig. 1; and

Fig. 4 is a side elevational view, on an enlarged scale, of one of the individual top links of the

chain taken from the right hand side of Fig. 1.

I claim:

The ornamental design for an expansible link chain for a bracelet or the like, as shown.

MAX JACOBY.
